ATTORNEY

UNITED STATES PATENT OFFICE.

GEORGE K. THOMPSON, OF MAPLEWOOD, NEW JERSEY.

SICKLE.

Application filed October 31, 1927. Serial No. 229,811.

This invention relates to a sickle having a curved holder member on which a plurality of razor blades may be mounted in an alignment corresponding to the curvature of said member, and in such manner that they can be readily replaced individually or collectively. The invention is more particularly concerned with an improved arrangement of this character, which is simple and inexpensive in operation. It consists in a holder provided with securing means by which a plurality of blades may be held in position, and said blades may be ordinary discards from safety razors.

The invention may be more fully understood from the following description, when considered in connection with the accompanying drawing in which certain modifications thereof are illustrated.

Referring to the drawing, Figure 1 is a side elevation of one modification of the improved device; Fig. 2 is an enlarged section thereof; Fig. 3 is a fragmentary view of a modification of Figs. 1 and 2, and Fig. 4 is an enlarged section on line 4—4 of Fig. 3.

In the drawing, in which like characters of reference designate like parts throughout, the numeral 5 represents a curved holder member corresponding to the formation of an ordinary sickle. A handle 6 is provided for the holder 5 and is attached thereto in any customary manner. The holder 5 may be composed of any suitable metal and comprises two parallel plates 7 and 8. These plates are oppositely positioned with respect to each other as indicated in Figs. 1 and 2. The plates 7 and 8 are provided with flanges 9 and 10, respectively, which overlap each other. The flat portions of the plates 7 and 8 extend from the flanges 9 and 10 and terminate in abutting shoulders. A rectangular chamber 11 is thus provided between the plates for a purpose to be presently described. The plates 7 and 8 have portions 14 and 15 which extend from said shoulders, and the outer surface of these portions may assume a somewhat tapered surface which terminates in a rather dull point. The inner surfaces of the portions 14 and 15 have flat opposing faces which lie closely adjacent each other.

Bolts 16 extend through apertures which

are provided in the plates 7 and 8 throughout their length, and these bolts may be provided with flat heads which rest against the outer surfaces of one of the plates. The ends of said bolts are provided with nuts which rest against a like surface of the opposite plate. The bolts, in the present instance for the purpose of illustration are indicated as positioned near the flanged portions of the plates. These bolts serve when tightened to exert pressure on said plates to securely clamp the two plates together. The parallel plates 7 and 8 may terminate at the end 17 of the blade in any desired shape, for instance, as indicated. The plates at the end 18, near the handle 6, may also terminate in any desired manner. For instance, said plates may be joined together to form a common tang extending into the handle 6, or said plates may be clamped together and to a tang.

The curved holder member 5 is adapted to have a series of any form or combination of safety razor blades attached thereto. For instance, the reference characters 19 indicate "Gem" razor blades in position in the holder 5. The character 20 shows a "Gillette" razor blade in position, and the character 21 an "Auto-Strop" razor blade in position. The safety razor blades may be attached to the curved holder 5, end to end, to form a series, and thus provide a continuous curved cutting edge conforming to the shape of the holder 5. The chamber 13 provides sufficient space to permit the entrance of a razor blade having an enlarged side such for instance as the "Gem" razor blade, as more clearly indicated by the reference 19 in Fig. 2. In this figure, a razor blade of the same thickness throughout, sometimes called a "wafer" blade such as the "Gillette" blade, is shown in dotted lines and indicated by the character 20. The portions 14 and 15 are of such width that they permit a sufficient extension of the cutting edges of the mounted blades therefrom to allow the blades to operate efficiently in cutting grass and not to be distorted by bending in such operation.

To place the blades in position in the holder 5, the nuts on the bolts 16 are loosened to permit the plates 7 and 8 to be sufficiently separated to allow the insertion of the

safety razor blades. After the blades are in position, the nuts are tightened and the plates are brought together to securely clamp the blades between them. When so clamped proper rigidity is provided for the blades to give them sufficient stiffness and prevent them bending while in operation.

In the modification shown in Figs. 3 and 4 two parallel plates 22 and 22' are provided which are in the general form of a sickle. These plates have one of their edges beveled, and said plates form a holder to which a series of "Gillette" blades is affixed. The series of blades may extend from near the tip of the holder to a point near its handle. A series of alined openings 23 is provided throughout the lengths of the plates of the holder, and these openings are located at definite intervals from each other to correspond to the intervals of the openings in the "Gillette" blades. The openings in the plates 22 and 22' of the holder are so located to permit sufficient extension of the cutting edges of the mounted blades therefrom. The extension of the mounted blades from the holder is such that a comparatively stiff and continuous cutting edge is effected. The ends of the "Gillette" blades 20 may overlap each other, as indicated in Fig. 3. In such overlapped position the mounted blades reenforce each other and provide such rigidity that they will be practically unaffected by bending while in operation. The razor blades may be clamped between the

plates 22 and 22' of the holder by means of 35 a bolt 24, which extends through plates 22' and engages the opposite plate 22 in threaded relation as indicated in Fig. 4, or in any other suitable manner.

From the foregoing, it is thought that the 40 construction, operation and many advantages of the herein described and delineated invention will be apparent to those skilled in the art, without further description, and it will be understood that various changes 45 in the size, shape, proportion and minor details of construction may be resorted to without departing from the spirit, or sacrificing any of the advantages of the invention, as defined in the appended claim. 50

What is claimed is:

The combination of a sickle having a curved holder and a handle therefor, said holder comprising a pair of parallel plates provided with a series of openings spaced at 55 definite intervals from each other, the openings in each plate being alined with those of the opposite plate, a series of separate cutting instruments removably mounted between the plates of said curved holder, and 60 means extending through said openings for clamping said cutting instruments to said holder to form a continuous cutting edge conforming to the curvature of the holder.

In testimony whereof, I have signed my 65 name to this specification this 29th day of October 1927.

GEORGE K. THOMPSON.
